UNITED STATES PATENT OFFICE.

ALFRED E. BARTLETT, OF OGDENSBURG, NEW YORK, ASSIGNOR OF ONE-THIRD TO RICHARD SPRY AND ONE-THIRD TO ALDERIC M. CORMIER, BOTH OF OGDENSBURG, NEW YORK.

GUARD FOR PAPER-WINDING MACHINES.

Application filed March 18, 1925. Serial No. 16,378.

To all whom it may concern:

Be it known that I, ALFRED E. BARTLETT, a citizen of Great Britain, residing at Ogdensburg, in the county of St. Lawrence 5 and State of New York, have invented certain new and useful Improvements in Guards for Paper-Winding Machines, of which the following is a specification.

This invention relates to an improvement 10 in guards for paper winding machines and more particularly to paper winding machines of the type known as, "double drum winder", wherein a reel of paper is mounted on a shaft carried by journal boxes which 15 are capable of vertical movement as the reel increases in size.

The object of the invention is to provide an automatic guard for the reel of paper being wound which, as the size of the reel 20 increases, will maintain a given clearance between it and the reel of paper, thereby insuring ample protection to the operator.

In the accompanying drawings,

Fig. 1 is a side elevation of the paper 25 machine with the attachment applied;

Fig. 2 is an enlarged transverse sectional view through the guard;

Fig. 3 is a detailed front view of one of 30 the feed rollers showing the stationary guard and the movable guard partly broken away;

Fig. 4 is a longitudinal section taken on the line, 4—4, of Fig. 1.

The numeral, 1, indicates the face of the 35 machine and projecting upwardly therefrom, are the standards, 2, constituting the frame work of the machine and supporting the journal bearings of the several machine shafts. The numerals, 3 and 4, indicate the 40 winding drums.

The numeral, 5, designates suitable guide-ways secured to the vertical faces of the standards, 2, and slidably received upon these ways are the journal boxes, 6, adapted 45 to support a shaft, 7, upon which the reel of paper, 8, is to be wound. The numeral, 9, indicates a stationary guard plate which surrounds the feed roll, 4. Secured to the ends of the guard plate, 9, are the semi-circular guide plates, 10—10, each having an inwardly projecting flange, 11. At the ends and intermediate of the stationary guard plates, 9, are arranged sets of rollers, 12,

rotatably journaled in suitable angle plates, 13—13. Received upon these rollers, 12, is 55 a movable semi-circular guard plate, 14.

As a means for actuating this movable guard plate, 14, as the reel of paper increases in diameter, I preferably provide the following mechanism.

The numeral, 15, indicates a vertically arranged arm secured to the journal box, 6, the lower end of said arm passing through suitable openings in the face to insure a true vertical movement. Secured to this 65 arm, 15, is a cam, 16. Pivoted as at 17, is a lever, 18, and rotatably secured to one end of this lever is a roller, 19, adapted to engage the cam, 16. The opposite end of said lever is connected by a link, 20, to the movable guard, 14, which owing to the contour of the cam is caused to recede as the cam, 16, moves upwardly due to the increasing diameter of the reel of paper being wound upon the shaft, 7. A counter weight, 21, 75 adjustably secured to the lever acts to return the movable guard as the cam, 16, moves in a downward direction.

In constructing a guard as hereinbefore described and illustrated, I have produced 80 a device which is simple in construction and effective in functioning to safeguard against accident to the operator.

It is obvious that more or less slight changes might be made without departing 85 from the general scope of my invention, therefore I do not wish to be limited to the exact structure disclosed.

I claim:

1. Guarding mechanism including a stationary guard, guide plates secured thereto and having inwardly extending flanges spaced apart from said stationary guard, anti-friction rollers securely carried by said stationary guard, and a movable guard interposed between said inwardly extending flanges and the anti-friction rollers, and movable relative thereto.

2. Guarding mechanism including a substantially arcuate stationary guard adapted 100 to protect a roller, a similarly shaped movable guard associated with said stationary guard, means connected with and extending outwardly from said stationary guard for guiding the movement of the movable guard, and means for moving the movable guard 105

- outwardly from the stationary guard, providing an extensible guarding means for protecting varying surfaces of the roller.
3. In a machine for winding paper, the combination with winding means, of a stationary guard for said winding means, a movable guard associated with said stationary guard, means connected with and extending outwardly from said stationary guard for guiding the movement of the movable guard, and means for moving the movable guard outwardly from the stationary guard, providing an extensible guarding means for protecting adjustable and varying portions of the winding means.
4. In a machine for winding paper, the combination with winding means, of a movable guarding means for said winding means, and cam actuated means connected with and actuated by said winding means for moving said movable guarding means.
5. In a machine for winding paper, the combination with winding means, of a stationary guard for said winding means, a movable guard connected with said stationary guard, and a cam connected with and actuated by said winding means for moving said movable guard.
6. In a machine for winding paper, the combination with winding means, of a stationary guard for said winding means, a movable guard connected therewith, rollers interposed between the stationary and movable guards, and means for moving said movable guard.
7. In a machine for winding paper, the combination with a winding shaft for receiving a paper roll, of winding drums, movable journal boxes for said winding shaft, a movable guard for said winding drums, and a movable cam connected with and actuated by one of said movable journal boxes, and connected with the movable guard for moving said guard as the size of the paper roll changes.
8. In a machine for winding paper, the combination with a winding shaft for receiving a paper roll, of winding drums, movable journal boxes for said winding shaft, a stationary guard for one of said winding drums, a movable guard connected with said stationary guard, and a movable cam connected with and actuated by one of said movable journal boxes, and connected with the movable guard for moving said guard as the size of the paper roll changes.
9. In a machine for winding paper, the combination with a winding shaft for receiving a paper roll, of winding drums, a stationary guard for one of said winding drums, a movable guard connected with said stationary guard, and means actuated simultaneously with a change in the size in the paper roll for moving said movable guard.
10. In a machine for winding paper, the combination with a winding shaft, of winding drums, a movable guard for one of said winding drums, and a cam operatively connected with said winding shaft for actuating said movable guard.
11. In a machine for winding paper, the combination with a winding shaft, of winding drums, a movable guard for one of said winding drums, a cam operatively connected with said winding shaft and operated by a movement thereof, and means operatively connected with said cam and connected with said movable guard for transmitting the movement of said cam to said movable guard.
12. In a machine for winding paper, the combination with a winding shaft, of winding drums, a movable guard for one of said winding drums, a cam operatively connected with, and operated by a movement of, said winding shaft, and means engaging said cam and flexibly connected with said movable guard for transmitting the movement of said cam to said movable guard.
13. In a machine for winding paper, the combination with a winding shaft, of winding drums, a stationary guard for one of said winding drums, a movable guard operatively connected with said stationary guard, a cam operatively connected with, and operated by a movement of, said winding shaft, and means operatively engaging said cam and flexibly connected with said movable guard for transmitting the movement of said cam to said movable guard.
14. In a machine for winding paper, the combination with a winding shaft upon which the paper roll is to be formed, of winding drums for supporting the winding shaft and paper roll during the winding operation, vertically movable journal boxes for said winding shaft, a semi-circular movable guard for one of said winding drums, a vertically movable cam carried by one of said winding roll journal boxes, and means interposed between said cam and semi-circular movable guard for imparting a receding movement to said guard as the diameter of the paper roll increases.
15. In a machine for winding paper, the combination with a winding shaft, upon which the paper roll is to be formed, of winding drums for supporting the winding shaft and paper roll during the winding operation, vertically movable journal boxes for said winding shaft, a stationary guard for one of the winding rolls, a movable guard supported by said stationary guard adapted to extend between said stationary guard and paper roll, and means actuated by the vertically movable journal boxes for imparting a receding movement to said movable guard as the diameter of the paper roll increases.

16. In a machine for winding paper, the combination with a winding shaft upon which the paper roll is to be formed, of winding drums for supporting the winding shaft and paper roll during the winding operation, vertically movable journal boxes for said winding shaft, a stationary guard for one of the winding rolls, a movable guard supported by said stationary guard adapted to extend between said stationary guard and paper roll, a cam carried by one of said journal boxes, a pivoted lever and link interposed between said cam and movable guard for actuating the latter with the upward movement of the paper roll.

17. In a machine for winding paper, the combination with a winding shaft upon which the paper roll is to be formed, of winding drums for supporting the winding shaft and paper roll during the winding operation, vertically movable journal boxes for said winding shaft, a stationary guard for one of the winding rolls, a movable guard supported by said stationary guard adapted to extend between said stationary guard and paper roll, an arm secured to one of said journal boxes and capable of vertical movement therewith, a cam secured to said arm, a pivoted lever actuated by said cam, a link connecting said lever and movable guard whereby the said movable guard is caused to recede as the diameter of the paper roll increases.

18. In a machine for winding paper, the combination with a winding shaft upon

which the paper roll is to be formed, of winding drums for supporting the winding shaft and paper roll during the winding operation, vertically movable journal boxes for said winding shaft, a semi-circular stationary guard for one of said winding rolls, rollers mounted upon said stationary guard, a semi-circular guard movable upon said rollers adapted to extend from said stationary guard to the paper roll, and means actuated by said vertically movable journal boxes for causing said semi-circular guard to recede as the diameter of the paper roll increases.

19. In a machine for winding paper, the combination with a winding shaft upon which the paper roll is to be formed, of winding drums for supporting the winding shaft and paper roll during the winding operation, vertically movable journal boxes for said winding shaft, a semi-circular stationary guard for one of said winding rolls, rollers mounted upon said stationary guard, a semi-circular guard movable upon said rollers adapted to extend from said stationary guard to the paper roll, a vertically movable cam carried by one of said journal boxes, a pivoted lever actuated by said cam and connected to said movable guard whereby the latter is caused to recede with the upward movement of said journal boxes.

In testimony whereof I affix my signature.

ALFRED E. BARTLETT.
